BOTTLE CARRIER

Paul Johansen, Crescent City, Ill.

Application March 24, 1936, Serial No. 70,695

2 Claims. (Cl. 215—100)

My invention relates generally to means for suspending and carrying bottles of the type which have laterally extending lips on the neck thereof, and particularly to a combination of rigid and flexible means forming a readily attached and detached handle, and an important object of my invention is to provide a simple, efficient, and inexpensive arrangement of this character.

Other important objects of my invention will be apparent from a reading of the following description in connection with the drawing, wherein for purposes of illustration I have shown a preferred embodiment of my invention.

In the drawing:—

15 Figure 1 is an elevational view of the neck of a milk bottle showing an embodiment of the invention mounted thereon.

Figure 2 is a plan view showing the embodiment with portions arbitrarily arranged to show the structural and functional relation thereof.

20 Referring in detail to the drawing, the numeral 5 generally designates the embodiment which comprises a semi-circular handle 6 having eyes 7 and 8 at its opposite ends to which the opposite ends of a cord generally designated 9, or a double cord, are attached as indicated by the numerals 10 and 11.

One end or flight 12 of the single or double cord passes slidably through a small ring 13 and 30 through another small ring 14 in similar free sliding manner and is then knotted as indicated by the numeral 15 to one side of the small ring 13.

The remaining flight 16 of the single or double cord 9 is freely and slidably passed through a 35 small ring 17 then similarly through the already mentioned small ring 14 and then knotted as indicated by the numeral 18 to one side of the ring 17, thereby defining a length 19 of single or double cord which extends between the small 40 rings 17 and 13 and is thereby of a fixed length, while all other portions of the cord have inconstant length relationships with each other. The fixed length of the cord portion 19 may advantageously be slightly less than half of the circumference of the neck 20 of the bottle 21 below the laterally extending lip 22 under which the fixed length 19 and the extensible lengths 12 and 16 of the cord 9 are circumferentially placed around the neck of the bottle.

45 In disposing the device to place the same upon the neck of the bottle in suspending and holding condition, the rings 13, 14, and 17 may conveniently be disposed in the relation shown in Figure 2 and the rings then dropped under the lip

22 of the bottle, with the fixed length portion 19 around one side of the neck and the flights 12 and 16 around the opposite side of the neck of the bottle. In order to snug these portions of the cord and the rings, it is simply necessary to pull upwardly on the handle 6. This will cause the cord or cords to constrict upon the bottle neck below the outstanding lip, so that the bottle can then be carried by holding the handle 6. To release the device from the bottle it is necessary simply to relax the pull on the handle 6 and then to pull slightly in a radially outward direction upon the middle ring 14, whereupon the device may be lifted from the bottle.

5 Although I have shown and described herein 15 a preferred embodiment of my invention, it is to be definitely understood that I do not desire to limit the application of the invention thereto, and any change or changes may be made in the materials, and in the structure and arrangement 20 of the parts, within the spirit of the invention and the scope of the subjoined claims.

What is claimed is:—

1. A device for suspending and carrying a 25 bottle having a neck equipped with a laterally outstanding lip, said device comprising a handle, and an elongated flexible member having its respective opposite ends fixed to spaced points on the handle, said flexible member comprising flights of cord, a pair of rings fixedly connected to the cord, a third ring freely connected to the cord, a double flight of the cord connecting the fixed rings with the free ring and a single flight of cord connecting the fixed rings, and said flights of cord between the fixed and free rings cooperating to surround the neck of the bottle in gripping engagement therewith.

30 2. A device for suspending and carrying a 40 bottle having a neck equipped with a laterally outstanding lip, said device comprising a handle, and an elongated flexible member comprising lengths of cords, a pair of relatively fixed apertured members, and a relatively free apertured member, certain lengths being fixed to said pair of fixed apertured members and passed freely through said free apertured member, and also passing freely through said fixed apertured members for attaching to the ends of the handle and another length being fixed to said pair of fixed apertured members, said lengths of said flexible 45 member cooperating to surround the neck of the bottle in gripping engagement therewith.

PAUL JOHANSEN.
